UNITED STATES PATENT OFFICE

128,782

DESIGN FOR A TOWEL BAR POST

Gustave A. Hallenscheid, Los Angeles, Calif.

Original application November 13, 1939, Serial No.
88,222. Divided and this application December
23, 1940, Serial No. 97,554

Term of patent 14 years

To all whom it may concern:

Be it known that I, Gustave A. Hallenscheid, a citizen of the United States, residing at Los Angeles, county of Los Angeles, State of California, have invented a new, original, and ornamental Design for a Towel Bar Post, of which the following is a specification, and which invention is a division of my application Serial No. D-88,222, filed November 13, 1939, reference being had to the accompanying drawing, forming a part thereof.

I claim:

The ornamental design for a towel bar post, as shown.

GUSTAVE A. HALLENSCHEID.
